(57) **CLAIM**

The ornamental design for a cleaning machine, as shown and described.

DESCRIPTION

FIG. 1 is a front view showing a first embodiment of a cleaning machine;

FIG. 2 is a rear view of FIG. 1;

FIG. 3 is a left side view of FIG. 1;

FIG. 4 is a right side view of FIG. 1;

FIG. 5 is a top view of FIG. 1;

FIG. 6 is a bottom view of FIG. 1;

FIG. 7 is a perspective view of FIG. 1;

FIG. 8 is a front view showing a second embodiment of a cleaning machine;

FIG. 9 is a rear view of FIG. 8;

FIG. 10 is a left side view of FIG. 8;

FIG. 11 is a right side view of FIG. 8;

FIG. 12 is a top view of FIG. 8;

FIG. 13 is a bottom view of FIG. 8;

FIG. 14 is a top perspective view of FIG. 8; and,

FIG. 15 is a bottom perspective view of FIG. 8.

(Continued)

The dotted lines in the figures show portions of the cleaning machine which form no part of the claimed design.
